(57) **CLAIM**

The ornamental design for a steering wheel for a vehicle, as shown and described.

DESCRIPTION

FIG. 1 is a perspective view of the front, top and right of the steering wheel for a vehicle;

FIG. 2 is a front elevational view thereof;

FIG. 3 is a right side elevational view thereof, the left side elevational view being a mirror image of FIG. 3;

FIG. 4 is a rear elevational view thereof;

FIG. 5 is a top plan view thereof;

FIG. 6 is a bottom plan view thereof; and,

FIG. 7 is a perspective view of the rear, bottom and left thereof.

The claimed design is indicated by the relatively dark portions in the figures, while the relatively light portions surrounded by broken lines form no part of the claimed design.

The article of the present design relates to a steering wheel for a vehicle that includes a rim that is provided with a grip portion in the outer peripheral edge, and a cushioning portion that has a cushioning property and against which a vehicle occupant can lean for a rest.

1 Claim, 7 Drawing Sheets
